UNITED STATES PATENT OFFICE.

GEORGE A. HOOVER, OF SALLISAW, OKLAHOMA.

PHONOGRAPH ARM AND HORN ATTACHMENT.

1,306,182.

Specification of Letters Patent. Patented June 10, 1919.

Application filed October 16, 1918. Serial No. 258,474.

To all whom it may concern:

Be it known that I, GEORGE A. HOOVER, a citizen of the United States, residing at Sallisaw, in the county of Sequoyah and State 5 of Oklahoma, have invented a certain new and useful Improvement in Phonograph Arm and Horn Attachments, of which the following is a specification.

My invention relates to improvements in 10 phonograph arm and horn attachments.

It relates particularly to the type of phonograph having a casing in which a horn is mounted and in which the reproducer arm is pivoted on the horn so as to swing vertically 15 and laterally.

One of the objects of my invention is to provide novel means for adjusting the horn to different positions so as to vary the distance between the reproducer arm and the 20 record table.

Another object of my invention is the provision of novel means for pivotally supporting the horn and acoustically insulating it from the casing.

25 Still another object of my invention is the provision of means for pivotally supporting the horn and holding the side walls of the casing from lateral movement by means of the horn support.

30 Another object of my invention is the provision of a novel joint for connecting the horn and reproducer arm and by which dust is excluded from the joint.

The novel features of my invention are 35 hereinafter fully described and claimed.

In the accompanying drawings, which illustrate the preferred embodiment of my invention,

Figure 1 is a view partly in vertical section 40 and partly in side elevation of my improvement in phonograph arm and horn attachments, shown mounted in a casing of an ordinary type.

Fig. 2 is a vertical sectional view on the 45 line 2—2 of Fig. 1, the record table being removed.

Fig. 3 is an enlarged cross section on the line 3—3 of Fig. 2.

Fig. 4 is an enlarged vertical sectional 50 view on the line 4—4 of Fig. 2.

Fig. 5 is an enlarged view partly in plan, partly in horizontal section and partly broken away, showing the reproducer arm 55 and parts connected therewith.

Fig. 6 is a vertical section on the line 6—6 of Fig. 7.

Fig. 7 is a vertical section on the line 7—7 of Fig. 6.

Fig. 8 is a cross section on the line 8—8 60 of Fig. 7.

Similar reference characters designate similar parts in the different views.

1 designates an ordinary phonograph casting having mounted in it a horn 2 of the usual 65 type. The casing 1 is provided with a floor 3, above which is an ordinary horizontal revolvable record support comprising a table 4 adapted to carry a disk record 5.

The floor 3 is provided with an opening 6, 70 through which the receiving end of the horn 2 extends and is vertically adjustable as hereinafter described.

As shown in Figs. 6 to 8, the upper or receiving end of the horn 2 is provided with 75 a connecting member 7 having at its upper end a spheroidal head 8 fitted for universal movement in a recess provided in the under side of a downwardly facing socket portion 9 of a horizontal tubular reproducer 80 arm 10. The socket portion 9 has mounted in it two diametrically opposite pivot members, preferably comprising screws 11 which extend into a horizontal peripheral groove 12 provided centrally in the spheroidal head 85 8. The latter is provided in the groove 12 at opposite sides respectively of one of the screws 11 with two abutments 13 adapted to strike the adjacent screw and limit the lateral swinging of the arm 10. The member 7 is provided with a peripheral shoulder 14, upon which the socket portion 9 is adapted to rest so as to hold the sound box casing 15 out of contact with the record 5 when no stylus or needle is mounted in the 95 stylus holder of the stylus bar 16 which is mounted on the sound box 15.

For mounting the horn 2 so that it can be so adjusted as to move the reproducer arm 10 toward or from the record table 4, I preferably provide a support which is pivoted to the side walls of the casing and which carries the horn and is provided with suitable adjusting means for swinging the support on a horizontal axis.

In the preferred embodiment of my invention, as shown in the drawings, the horn support and its adjusting means comprise the following described parts.

17 designates a substantially rectangular 110

vertical frame through which the horn 2 extends. Extending vertically through the top of the frame 17 is a bolt 18, both ends of which are screw-threaded and provided respectively with nuts 19 and 20, as shown in Figs. 1 and 2.

The upper side of the horn 2 is provided with a hole 21 through which the bolt 18 extends, and which is of sufficient diameter to prevent the bolt 18 having contact with the horn. Encircling the bolt 18 and clamped against the inner side of the horn 2 by the nut 20 is a collar 22 of soft rubber, felt or other poor sound conductor. Clamped against the outer side of the horn 2 and encircling the bolt 18 is a collar 23 similar to the collar 22. Bearing against the collar 23 and the frame 17 is a collar 24 which may be of wood or metal. The manner of supporting the horn 2 above described serves to acoustically insulate the horn at the point of support from the frame 17.

The frame 17, as shown in Fig. 2, at its opposite sides is provided with two laterally oppositely extending trunnions 25, each of which is provided with a vertical arm 26 having a vertical slot 27, through which extend two clamping screws 28, the threaded inner ends of which are mounted in threaded holes provided therefor in the adjacent side of the frame 17. By loosening the screws 28, the trunnions 25 can be vertically adjustable to desired positions on the frame 17 and then retained in said positions by tightening the screws 28.

For pivotally supporting the trunnions 25 in a manner such that the latter will hold the side walls of the casing 2, from lateral movement due to rough handling in shipping or otherwise, I provide two bearing plates 29, which are respectively secured in any suitable manner, as by screws 30, to the inner sides of the side walls of the casing 2. Each bearing plate 29 is provided with a vertical slot 31 having an enlarged upper end adapted to receive a head 32 which is provided at the outer end of adjacent trunnion 25. The head 32 is of larger diameter than the lower end of the slot 31, but is of less diameter than the upper portion of said slot. At the inner side of the head 32 each trunnion is provided with a peripheral groove 33 into which adjacent bearing plate 29 is adapted to slip. In assembling the attachment, the heads 32 are slipped through the enlarged upper ends of the slots 31, after which the plates are slipped into the grooves 33, following which the bearing plates 29 are fastened to the inner sides of the casing, as shown in Fig. 2. When so assembled, the side walls of the casing are held from spreading and the frame 17 is pivotally supported.

Extending rearwardly and upwardly from the lower part of the frame 17 is an

arm 34 having a screw-threaded upper end which extends through a hole 35 in the floor 3, and which has mounted on said threaded end a nut 36 having a peripheral grooved portion 37 rotatably and slidably mounted in a slot 38 provided in a horizontal plate 39 secured to the upper side of the floor 3 over the hole 35.

By adjusting the nut 36 on the arm 34, the frame 17 may be swung on its axis to different positions, thereby swinging the upper end of the horn 2 upwardly or downwardly, so as to raise or lower the arm 10 with respect to the table 4. By means of this adjustment, the sound box 15 may be adjusted to the proper position adapted for the proper operation of the stylus or needle 40 on the record 5. To permit the nut 36 to have the necessary sliding movement in the plate 39, the slot 38 extends to the rear edge of the plate 39. The holes 6 and 35 are of sufficient diameter to permit the horn 2 and nut 36 to have the desired adjustment.

For additionally supporting the horn 2, there may be provided a bolt 41, Fig. 1, which is screw-threaded at both ends and has mounted on it two nuts 42 and 43. The bolt 41 extends through the arm 34 and through but not touching the adjacent wall of the horn 2. The nut 43 bears against the rubber washer 44, which bears against the inner side of the horn. A similar washer 45 bears against the outer side of the horn, said two washers being mounted on the bolt 41. A collar 46 encircles the bolt 41 and bears against the arm 34 and washer 45.

The horn 2 is thus supported by but acoustically insulated from the arm 34.

The needle 40 is disposed at the rear of a vertical plane extending through the trunnions 25. Thus by turning the nut 36, the upper end of the arm 34 may be raised or lowered, thereby swinging the frame 17 on its axis so as to raise or lower the arm 10 through the intermediacy of the horn 2 and the ball and socket joint connecting the arm with the horn.

By means of the mounting of the horn in the casing as described, the horn and the reproducer arm are both acoustically insulated from the casing, while at the same time being adjustable in the casing to different positions.

I do not limit my invention to the structure shown and described, as modifications, within the scope of the appended claims, may be made without departing from the spirit of my invention.

What I claim is:

1. The combination with a phonograph horn, of a reproducer arm carried thereby, a casing, a record table in the casing, and a support for the horn pivoted to the casing having a screw-threaded arm and a nut mounted on the arm engaging the casing for 125

adjusting the support on its pivots to different positions for varying the distance between the reproducer arm and the record table.

5. 2. The combination with a phonograph horn, of a reproducer arm carried thereby, a casing having a floor below the reproducer arm and provided with an opening through which the horn extends and is vertically adjustable, a record table intermediate of said floor and said reproducer arm, and means carrying said horn and pivoted on a horizontal axis to said casing and provided with means for adjustment to different positions 15 on its axis for varying the distance between the reproducer arm and the record table.

3. The combination with a phonograph horn, of a reproducer arm carried thereby, a casing having a floor below the reproducer 20 arm and having an opening through which the horn extends and is adjustable vertically, a record table intermediate of the reproducer arm and the floor, and a support pivoted to the casing on a horizontal axis and 25 carrying the horn and having a screw threaded arm and a nut fitted to said threaded arm and engaging said floor for swinging the support to different positions on its axis so as to vary the distance of the 30 reproducer arm from the record table.

4. The combination with a phonograph horn, of a casing, and a support for the horn pivoted to the side walls of the casing and having means for holding the side walls 35 from lateral movement.

5. The combination with a phonograph horn, of a casing, and a support carrying the horn and pivoted on a horizontal axis to the casing and having adjustable means engag- 40 ing the casing for holding the support in

such positions to which the support may be swung.

6. The combination with a phonograph horn, of a casing having a floor, provided with an opening through which the horn extends and is vertically adjustable, and a support pivoted on a horizontal axis to the casing and carrying the horn. 45

7. The combination with a phonograph horn, of a casing having a floor provided with an opening through which the horn extends and is vertically adjustable, and a support for the horn pivoted on a horizontal axis to the casing and having a screw threaded arm and a nut mounted on the 55 threaded arm and rotatably engaging the casing.

8. The combination with a phonograph horn, of a casing having a floor provided with an opening through which the horn extends and is vertically adjustable and provided with a plate having a slot, and a support carrying the horn and pivoted on a horizontal axis to the casing and having a screw threaded arm and a nut mounted on 60 the arm and rotatably and slidably mounted in said slot. 65

9. The combination with a phonograph horn, of a casing, provided with two bearing plates on opposite inner walls respectively, 70 and a support for the horn having two laterally extending trunnions respectively pivoted in said bearing plates and having means for engaging said plates to hold the trunnions from endwise movement with respect 75 to said plates.

In testimony whereof I have signed my name to this specification.

GEORGE A. HOOVER.
